UNITED STATES PATENT OFFICE.

JOHN G. ERNST, OF BALTIMORE, MARYLAND, ASSIGNOR OF ONE-HALF TO
JEREMIAH D. MALLORY, OF SAME PLACE.

CAR-AXLE BOX.

SPECIFICATION forming part of Letters Patent No. 282,871, dated August 7, 1883.

Application filed March 1, 1883. (No model.)

To all whom it may concern:

Be it known that I, JOHN G. ERNST, of Baltimore city, and State of Maryland, have invented a new and useful Improvement in Car-
5 Axle Boxes; and I do hereby declare that the following is a full, clear, and exact description of the same.

My invention relates to the lubrication of car-
10 axle boxes. In the standard car-axle box the
waste packing placed underneath the journal-
box becomes heavy with oil and settles, entirely
leaving the axle and resulting in the heating of
the box. This renders it necessary frequently
15 to stir up the packing and raise it on both
sides. Further, the oil, when poured into the
box as heretofore made, sinks to the bottom,
and has to be carried up all the way there-
from to the axle by capillary attraction.

The object of my invention is to suspend
20 the oil and the packing above the bottom of
the box, to hold them nearer the box, and to
prevent the packing from settling.

The invention consists in making this sus-
25 pending device in the form of a pan or recep-
tacle in the front part of the box, with gutters
running back on each side. The invention is
not limited to the particular construction, and
30 the shelf or pan and gutters may be cast with
the box, or may be cast separately for insertion
in the old boxes, all as hereinafter set forth.

In the accompanying drawings, Figure 1 re-
presents a side elevation of the box, with the
35 wall partly broken away. Fig. 2 is a longi-
tudinal vertical section with the axle in side
elevation. Fig. 3 is a transverse section. Fig.
4 is a plan of the shelf detached.

In these drawings the device which sustains
the packing is shown as a separate part adapt-
ed to be inserted into the ordinary box. The
40 device consists of a pan, A, in the front part
of the box, with a supporting-lip, a, which
curves back over the front of the box at the
lower part of the opening and supports the
45 pan thereon. On either side from the pan are
hollowed extensions or gutters b b, which run
back to the rear of the axle-box, the hollows
or gutters being closed at the rear ends and
opening at the front into the pan. The rear

ends of the extensions are supported upon legs
c c. The device may be located at any suit-
able height. I have shown it as set on a hori-
5 zontal line a little above the lower surface of
the journal; but it may be higher or lower
without departing from the spirit of my inven-
tion, and the detachable shelf or pan, with its
5 guttered extensions, may be supported by dif-
ferent devices than those shown and described.

As before stated, instead of making the de-
vice detachable, which adapts it to old forms
of boxes, I propose, in casting new boxes, to
6 form it integral with the box itself.

When the journal is in place under the bear-
ing, the waste packing is packed under the
axle, beneath the shelf and above, on either side.
The oil poured in from the front falls into the
6 pan, and from the pan runs into the guttered
extensions, where it is held at a proper height
near to the bearing and prevented from fall-
ing to the bottom of the box. The extensions
also sustain the packing and prevent that
7 from settling when it becomes heavy with oil.
Plain extensions or shelves would sustain the
packing equally well, but would not catch and
hold the oil and prevent it from going to the
bottom.

I am aware that an axle-box with sockets
for holding wipers, and that separate oil-boxes
adapted to sustain the packing, are not new.

Having thus described my invention, what
I claim is—

1. In an axle-box, a shelf formed or placed
within the box, consisting of a pan and chan-
neled extensions, adapted to receive and hold
the oil above the bottom of the box, and also to
support the packing, substantially as described. 8

2. The movable shelf consisting of the pan
A, guttered side pieces, b b, legs c c, and flange
a, all as set forth.

In testimony whereof I have signed my name
to this specification in the presence of two
9 subscribing witnesses.

JOHN G. ERNST.
